UNITED STATES PATENT OFFICE

SYLVESTER A. JOHNSON, OF NORTH PROVIDENCE, RHODE ISLAND, ASSIGNOR TO SPEIDEL BROS., OF PROVIDENCE, RHODE ISLAND, A FIRM COMPOSED OF ALBERT E. R. SPEIDEL AND EDWIN F. M. SPEIDEL, BOTH OF CRANSTON, RHODE ISLAND

EXTENSION DEVICE

Application filed May 31, 1930. Serial No. 458,841.

This invention relates to an extension device for use in connection with a bracelet, particularly a wrist watch bracelet, and has for its object to provide a resilient latch which may be formed of a material different from the material of the foldable sections in order that resiliency may be better retained.

A further object of this invention is to provide a latch member which may be formed of sheet stock and mounted upon the hinge means between two sections to hold the same in place.

A further object of this invention is the provision of means whereby a two-part bracelet with an extension device hinged to one part may be detachably connected to the other part so that a watch with bracelet parts extending from either side thereof may be laid flat upon a card, and the extension device which is secured to one end of one part of the bracelet may be easily assembled by a retail merchant by simple manual manipulation to attach the end of the other part of the bracelet to the extension device.

With these and other objects and advantageous features in view, the invention consists of a novel arrangement of parts more fully disclosed in the detailed description following, in conjunction with the accompanying drawings, and more particularly set forth in the appended claims.

In the drawings:

Fig. 1 is a top plan view of a watch with a two-part bracelet attached thereto, and an extension device at the end of one of the bracelet parts;

Fig. 2 is a bottom view thereof;

Fig. 3 is a bottom view of the extension device in unfolded position;

Fig. 4 is a section through line 4—4 of Figure 3;

Fig. 5 is a perspective view of the latch member; and

Fig. 6 is a sectional view through the extension device in folded position, showing the latch member in engaging position.

It is found desirable by watch manufacturers to mount their watches with bracelets attached thereto on a card, and it is also found desirable to use in connection with such

a bracelet an extension device whereby the watch may be removed from the wrist by passing the same over the hand without detachment of any of its parts. The watch manufacturer has heretofore not been able to use an extension device on his bracelet by reason of the same being permanently attached at both of its ends to the bracelet in which it was assembled. This invention overcomes this difficulty so that the watch manufacturer may use an extension device in the bracelet assembly by providing a detachable connection at one end of the extension device for engaging one end of a bracelet part so that the bracelet with watch assembled may lie flat upon a card and the jeweler when the same is sold may assemble the bracelet and extension device by a simple manual manipulation. I have also provided a separate latch member which may be mounted upon a pivot pin for connecting two of the sections, whereby the resiliency may be controlled by use of a different material than that of the sections; and the following is a detailed description of the present embodiment of this invention, illustrating the preferred means by which these advantageous results may be accomplished.

With reference to the drawings, 10 designates a wrist watch and 11 a link bracelet, parts of which are secured at each side of the watch by means of end hooks 12. An extension device 13 is connected to the end link 14 of one part of the bracelet and consists of a channel section 15 and flanged sections 16 and 17 hingedly connected to each other and to the section 15 by means of pivot pins 18 and 19, the section 17 being secured to the end link 14 by means of a pivot pin 20.

On the pivot pin 18 there is mounted a latch member 21 consisting of a sheet metal bent to form an eye 22 for mounting the same on the pivot pin 18 in the slot 27 formed in the section 16 to permit the same to move about its hinge mounting 18 without interference of the latch member. The material at one side of the eye is doubled back upon itself as at 23 and outwardly curved as at 24 to form a nose 25 to snap over the pin 20 and releasably hold the sections in folded posi-

tion, while the body portion 26 of the latch extends on the opposite side of the eye 22 and prevents movement in one direction of the eye about the pin 18 on which the latch is 5 mounted.

At the end of the section 15 to which the bracelet is connected there is mounted an endways movable pin 28 having an enlargement or washer 29 mounted thereon, with a 10 spring 30 encircling the pin 28 and acting between the side wall 31 of the section, and the washer 29 tending to move the washer into engagement with the wall 32. The end link 36 of one bracelet part has its side walls 33 15 and 34 pierced as at 37 and 38 to receive the pin 28. The watch, bracelet and extension device are mounted on a card in the connected relation shown in Figure 1, and the retail merchant or jeweler upon selling the same as 20 assembles the extension device and the link 36 by first inserting in the opening 37 in the side wall 33 over one end of the pin 28 and then pressing the pin inwardly as indicated by arrow 35, sliding the other wall 34 in place and 25 to cause its opening 38 in position, relaxing the pressure at 35 to permit the pin 28 to move by action of the spring 30 into the opening and secure the same in position. For detachment, the operation of assembly is reversed.

While I have described certain construction forms which embody the principles of my invention, it is obvious that other desired changes in arrangement may be made within 35 in the spirit and the scope of the invention as defined in the appended claims.

I claim:

1. An extension device comprising a plurality of sections, hinge means for connecting 40 said sections together to fold one on another, a separator resilient member having a latch portion extending therefrom mounted on the hinge means between two sections for resiliently engaging a part carried by another 45 section for holding said sections in folded position.

2. An extension device comprising a plurality of sections, pivot pins for hinging said sections together to fold one on another, a 50 separate resilient member having a portion embracing the pivot pin between two sections and with a latch portion extending therefrom for resiliently engaging a part carried by another section holding said sections in folded 55 position.

3. An extension device comprising a plurality of sections, pivot pins for hinging said sections together to fold one on another, a separate resilient latch member having an 60 eye to engage one of said pivot pins to mount the same thereon, and a resilient nose portion to snap over a pin carried by another section for holding the sections in folded position.

4. An extension device comprising a plurality of sections, pivot pins for hinging said 65

sections together to fold one on another, a separate resilient latch member having an eye to engage one of said pivot pins to mount the same thereon, and a portion doubled back on said eye and curved away therefrom to form a resilient nose portion to snap over a pin carried by another section for holding the sections in folded position.

5. An extension device comprising a plurality of sections, pivot pins for hinging said sections together to fold one on another, a separate resilient latch member having an eye to engage one of said pivot pins to mount the same thereon, a resilient nose portion to snap over a pin carried by another section for holding the sections in folded position, and an extension on the opposite side of said eye to limit movement thereof about the pin in one direction.

In testimony whereof I affix my signature.

SYLVESTER A. JOHNSON.
